UNITED STATES PATENT OFFICE.

ROBERT C. LEGAT, OF NEW BRITAIN, CONNECTICUT, ASSIGNOR TO THE G. E. PRENTICE MANUFACTURING COMPANY, A CORPORATION OF CONNECTICUT.

HANGER SUPPORT.

Application filed March 23, 1925. Serial No. 17,694.

To all whom it may concern:

Be it known that I, ROBERT C. LEGAT, a citizen of the United States, residing at New Britain, in the county of Hartford 5 and State of Connecticut, have invented certain new and useful Improvements in Hanger Supports, of which the following is a specification.

My invention relates to improvements in 10 hanger supports such as are adapted for use in such devices as key cases and the like in which the hanger is in the form of a hook-like clip that may receive and support a key or similar article and the support is such as can be incorporated in a 15 case of leather or the like and which by the cooperation of its own means of support and the connection with the hanger permits of relatively free operative movement 20 of the key or article, and the object of my improvement is to produce a combination in a hanger support that provides a swinging movement where desired on a shaft for the parts generally and a 25 rotative movement of the hanger, and all by means of parts that are relatively simple and economical to manufacture and convenient and efficient for use.

In the accompanying drawing:

30 Figure 1 is a front elevation of a hanger support and connected parts embodying my invention, supporting brackets for the shaft and part of a supporting body or back being indicated substantially diagrammatically.

Figure 2 is a side elevation on an enlarged scale of the hanger support and hanger, the shaft, of tubular form, being shown in section.

40 Figure 3 is a sectional view on the line 3—3 of Fig. 2.

Figure 4 is a plan view of the blank for the hanger support.

45 Figure 5 is a fragmentary front elevation of a modification of the hanger support on a shaft.

Figure 6 is a side elevation of the same.

Figure 7 is a plan view of the blank for the hanger support.

50 My improved hanger support 10 is adapted for use in supporting a hanger 11 of hook-like form and which may be designated as a clip and the preferred manner of support for the hanger support itself 55 is by means of a shaft 12. The latter may

be supported on brackets 13 of proper form that are themselves mounted on a body or back 14 that is part of a case or the like, and which may be made of leather or other suitable material. 60

As shown, the support 10 has a pair of opposed ears 15 that are pierced to provide openings 16 for the shaft 12.

The ears 15 are parts of a ball 17 that is made of sheet metal and are individually connected to said ball 17 by connecting necks 18 of reduced width. The ears 15 and necks 18 are extended outwardly along one of the diagonals of a square structure that constitutes the material for the ball 17, 70 the other diagonal terminating at the right-angled corners 19 that are formed by the meeting of the adjacent straight side edges 20. A square structure 17 of sheet metal such as shown, as is well known, can be 75 swaged to form a ball 17 so that as to this detail only a well known result is attained.

In the present instance the material of the square 17 or ball 17 is perforated at 80 the middle to provide an opening 21 for the shank 22 of the hanger 11.

Said shank 22 is projected through the opening 21 and has the upper end 23 curled over to provide operatively an enlarged 85 head that is finally enclosed loosely within the ball 17 so as to provide a relatively freely operative pivotal connection between the parts.

The pendant body portion or clip proper 90 24 of the hanger 11, as shown, is shaped as a spring-closed hook that encloses a space for the loop of a key or the like.

The described structure provides a relatively simple connection between the hanger 95 and the ball that operates as a ball and socket connection, which permits of turning an attached key and the pivotal connection with the shaft permits of swinging the hanger and connected device back and 100 forth, as from a position within a casing to one that is outside the same.

In the structure that is shown in Figs. 5, 6, and 7 the ball 17^a itself is formed like the ball 17 that has been described, but the integral connected structure differs in that there is only a single connected neck 18^a, the same being extended from one corner, and there are three full and complete corners 19^a that are folded up. 110

wardly and inwardly to enclose the head structure 23^a on the shank 22^a of the hanger 11^a.

Also, in lieu of an ear structure 15 that is perforated for the shaft 12 there is provided a diminutive plate-like structure 15^a that is curled into cylindrical form and operatively mounted on the shaft 12^a to permit of a swinging movement substantially after the manner described.

The pivotally mounted supporting sleeve 15^a described is laterally elongated and, as shown, such elongation is appreciably greater than the diameter of the ball 17^a, wherefore, said sleeve 15^a is adapted to serve as a spacer for the hanger and ball relatively to similar devices mounted on the same shaft, the opposed tip ends or end faces 26 meeting in abutment.

20 I claim as my invention:—

1. A hanger support for use with a key case, having a pendant portion in the form of a substantially hollow structure that is provided with an opening at the lower end, 25 a hanger for receiving a key having a shank of wire that is projected through said opening so that the free end portion is housed within said structure, and said free end portion being curled upon itself in the plane 30 of the shank without diminishing the cross sectional area thereof to provide an operative fit within said structure for cooperating therewith as a swivel connection.

2. A hanger support for use with a key case, having a pendant portion in the form of a hollow structure having an opening at the lower end, a hanger having a shank which is projected through said opening, the free end of said shank having a head positioned within said hollow structure for cooperation therewith to form a swivel connection, said hollow structure being made from a sheet metal blank having said opening therein, the blank being extended in substantially opposite directions on substantially opposite sides of the opening to provide portions which are bent up from the plane of said opening to confine said shank head and said extensions being each continued for attachment to a support.

3. A hanger support for use with a key case, having a pendant portion in the form of a hollow structure having an opening at the lower end, a hanger having a shank which is projected through said opening, the free end of said shank having a head

positioned within said hollow structure for cooperation therewith to form a swivel connection, said hollow structure being made from a sheet metal blank having said opening therein, the blank being extended in substantially opposite directions on substantially opposite sides of the opening to provide portions which are bent up from the plane of said opening to confine said shank head and said extensions being each continued for attachment to a support, said blank having additional extensions on opposite sides of said opening and in opposite directions at an angle to said first mentioned extensions, said last extensions being bent up to complete said hollow structure.

4. A hanger support for use with a key case, having a pendant portion in the form of a hollow structure having an opening at the lower end, a hanger having a shank which is projected through said opening, the free end of said shank having a head positioned within said hollow structure for cooperation therewith to form a swivel connection, said hollow structure being made from a sheet metal blank having said opening therein, the blank being extended in substantially opposite directions on substantially opposite sides of the opening to provide portions which are bent up from the plane of said opening to confine said shank head and said extensions being each continued for attachment to a support, said continuations of the extensions having registering perforations to receive a support.

5. A hanger support for use with a key case, having a pendant portion in the form of a hollow structure having an opening at the lower end, a hanger having a shank which is projected through said opening, the free end of said shank having a head positioned within said hollow structure for cooperation therewith to form a swivel connection, said hollow structure being made from a sheet metal blank having said opening therein, the blank being extended in substantially opposite directions on substantially opposite sides of the opening to provide portions which are bent up from the plane of said opening to confine said shank head and said extensions being continued for attachment to a support, said continuations of the extensions having registering perforations to receive a support and being in substantially facing contact.

ROBERT C. LEGAT.
